[57] CLAIM

The ornamental design for a combined window and fire escape, as shown and described.

DESCRIPTION

FIG. 1 is a front elevational view of the combined window and fire escape showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is a cross-sectional view taken along line 7—7 of FIG. 2, and includes a broken line showing of the device of the present invention in an extended operative orientation for illustrative purposes only and forms no part of the claimed design.
